UNITED STATES PATENT OFFICE.

HARRY W. ALLEN, OF CHICAGO, ILLINOIS, ASSIGNOR OF ONE-HALF TO
JOHN R. BENDER, OF SAME PLACE.

FISH-PLATE AND FASTENING.

SPECIFICATION forming part of Letters Patent No. 393,320, dated November 20, 1888.

Application filed March 23, 1888. Serial No. 268,294. (No model.)

To all whom it may concern:

Be it known that I, HARRY W. ALLEN, of Chicago, in the State of Illinois, have invented certain new and useful Improvements in Fish-
5 Plates and Fastenings, of which the following is a specification.

The invention relates to fish-plates and fastenings for securing the joints of railroad-rails; and the objects of my improvements are to provide fish-plates adapted to be applied to the sides and bottom of the rail without any perforations and to be secured thereto by bolts extending under the rail, and to provide a part through which the bolts pass adapted to catch
15 over the lower edge of the plate, and having means for locking the nut on the bolt.

The invention is illustrated in the accompanying drawings, in which—

Figure 1 is a cross-section of a T-rail, showing an end view of the fish-plates and the manner of applying the bolt to secure the same to the rail. Fig. 2 shows a side elevation of Fig. 1, the fish-plate being applied to the joint between rails. Fig. 3 is a fragment of a bottom view. Fig. 4 is a perspective view of the part through which the bolt passes. Fig. 5 is a fragment of a cross-section of a rail, with an end view of the plate in modified form.

A designates the T-rail, and A' the fish-plate, 30 which is designed to be made of spring steel. These plates consist of a flat bottom plate, a, adapted to rest on the tie which comes under the joint and to project under the rail nearly to its center, and the curved plate a', which is 35 made as an integral part of the flat plate a and curved so as to fit over the base flange of the rail when the flat plate is slid under it from the side. The part a' may be made so as to extend clear over the base-flange and up against 40 the side of the rail, as shown in Fig. 1, or only part way over the base-flange, as shown in Fig. 5. When extended up against the sides of the rail, the construction of the curved part should be such as to cause the upper edge, as at a', to 45 strike the rail a little in advance of the other portions, so that when drawn close up against the rail at the other points the upper edges will be sprung out slightly, and thereby be caused to clamp the rail tightly at this point 50 by the bringing of the other portions up against the rail.

B designates the part through which the bolt B' passes. This part has a slotted part, b, the upper surface, b', of which is adapted to fit on the under side of the plate a, and an upwardly-projecting part, b'', in which there is a groove, b'', adapted to fit over the outer edge of said plate a. Through the center at c there is a hole adapted to receive the bolt, which hole is in line with the slot c', so that the bolt will come 6c close up to or against the under side of the plate a, there being sufficient fullness at c' to give the necessary strength to prevent buckling when the bolt is tightly drawn. At the front is a groove, e, in which a flat narrow piece 65 of sheet metal, e', provided with a hole for the bolt to pass through, can be placed, so as to come under the nut e' on the end of the bolt, and when the nut is screwed home the outer ends of the metal, e', are bent outward over it, 70 so as to prevent its being turned or becoming loose, the part of e' under the nut and in the groove being stopped thereby from turning and the part bent over the nut keeping the latter from turning.

Two of the fish-plates A are applied at each joint, one upon each side of the rail, with a bolt under each end of the plate. Any common bolt of the required length may be used. The plates should not quite meet on the under 80 side of the rail, but sufficient space should be allowed to insure the full clamping effect of the bolts without bringing the edges of the plates snugly together under the rail.

I am aware of United States Patents to 85 Swett, No. 97,515, of June 30, 1868; to Loomis and Rhodes, No. 125,310, of April 2, 1872, and to Palmer, No. 182,448, of October 3, 1876; but my invention is not shown therein.

The part a' of the fish-plate of my invention 90 is set back from the outer edge of the part a, and said edge is thin, so that it may be secured to the tie by spikes the same as the rails are, without any holes, notches, or other formations at given points along the edge to adapt the 95 same to the spikes. The plate and part a' in this form can be rolled out in long bars and cut off in proper lengths ready for use without punching, drilling, or other process to adapt the same to the spikes.

The bolt parts B should be made in the form shown—that is, the slotted part b should be 100

extended perpendicular to the part b^2 and should have a fullness at the junction c^2 , opposite the groove b^3 , operating as a brace between the slotted part and the lower portion of said part b^2 ; and the hole c should register with the slot in the part b , as by this means the head and nut of the bolt b^1 are extended considerably above the lower line of said plates and made to bear directly or squarely against the edges of said plates, the body of the bolt coming against their bottom side. By this construction the parts are made much lighter than heretofore and without material diminution of strength, which affords a great saving of metal.

Having thus described my invention, what I claim, and desire to secure by Letters Patent, is—

The fish-plates consisting of the parts a and

a' , the latter being set back from the outer edge of the former, as shown, and the side pieces, B , consisting of the slotted part b and the part b' , made integral, said part b' being extended perpendicular to said part b and having a groove, b^1 , on one side and a fullness at its junction with the part b on the side opposite to said groove b^3 , a hole, c , which registers with the slot c^2 of said part b , and a groove, e , in its outer face, in combination with a screw-bolt, B' , and perforated sheet-metal pieces c' , adapted to said groove e , as and for the purpose specified.

HARRY W. ALLEN.
